UNITED STATES PATENT OFFICE.

RUDOLF FROMMER, OF BUDAPEST, AUSTRIA-HUNGARY.

EJECTOR FOR FIREARMS.

1,169,248.

Specification of Letters Patent. Patented Jan. 25, 1916.

Application filed November 7, 1913. Serial No. 799,649.

To all whom it may concern:

Be it known that I, RUDOLF FROMMER, residing at 158 Soroksári út, Budapest, IX, Austria-Hungary, manager, have invented 5 certain new and useful Improvements in Ejectors for Firearms, of which the following is a specification.

My invention relates to ejector for fire arms and the object of my invention is to 10 produce an ejector in which the ejecting force can be regulated. This is of great importance in the case of automatic fire arms and more especially in the case of rifles and machine-guns, in which the ejection 15 takes place with great force and the empty cartridge is thrown for a considerable distance, whereby persons standing nearby may be seriously endangered.

According to my invention, I make the 20 ejecting force controllable by arranging the ejector-hook in such a manner that it can give way against the action of a spring, as it is struck by an empty cartridge, so that by the use of a correspondingly strong 25 spring or by the adjustment of the strength of the said spring, it is possible to so regulate or control the force of the blow of the bottom of the cartridge against the ejector-hook that the empty cartridge is only 30 ejected with the necessary force, and the ejection, in instances where the recoil happens to be stronger than usual, is not much more forcible, as the spring acting on the ejector absorbs the surplus force.

35 A form of construction of my new ejector is shown by way of example on the accompanying drawing.

The hook shaped ejector *b* is inserted in

the breech casing *d* at *a* in such a manner that the hook portion of the ejector *b* can 40 give way against the action of the spring *c* as the hook portion is struck by the empty cartridge.

If the spring *c* is weak, the ejector will give way to such a considerable extent that 45 no ejection occurs. This is avoided if the tension of the spring *c* is increased or the spring replaced by a stronger one, in which case the ejector approaches the action of a rigid ejector or of one which is rigid at the 50 moment of ejection, whereby, as is well known, the most forceful ejection is produced. One can vary the force of the ejection to any desired degree by correspondingly choosing the spring *c* or by adjusting 55 its strength.

The scope of my invention is of course not limited to the illustrated construction, as the hook shape of the ejector is only 60 one of the many forms, it being only essential that the ejector can give way against the action of an exchangeable or adjustable spring when struck by the empty cartridge.

I claim as my invention:

In combination with the breech-casing of 65 fire-arms an ejecting lever pivotally inserted in the breech-casing with its forward end and having at its rear end a hook portion adapted to project into said breech casing into the path of the empty cartridge, and 70 a spring acting on said ejecting lever so as to normally force its hook portion into the breech casing.

In testimony whereof I affix my signature.

RUDOLF FROMMER.
